SPRAYER

Rome C. Seyforth, Lowell, Mich., assignor to
 Lowell Manufacturing Company, Lowell,
 Mich.

Application June 3, 1932. Serial No. 615,129

10 Claims. (Cl. 299—88)

The main objects of this invention are:

First, to provide a sprayer adapted to receive receptacles of different capacities, thereby permitting the receptacle to be merchandised as a unit, and avoiding the necessity of providing a complete sprayer for each size or capacity receptacle.

Second, to provide a sprayer which is very compact when disassembled from the receptacle for shipping or storage.

Third, to provide a sprayer having these advantages which is economical to produce and very strong and durable and convenient to use.

Objects relating to details and economies of my invention will appear from the description to follow. The invention is defined in the claims.

A structure which is a preferred embodiment of my invention is illustrated in the accompanying drawings, in which:

20 Fig. 1 is a fragmentary side elevation of a sprayer embodying the features of my invention, a receptacle of one capacity being shown by full lines, a larger receptacle being indicated by dotted lines.

25 Fig. 2 is an enlarged fragmentary view in longitudinal central section on line 2—2 of Figs. 3 and 7.

Fig. 3 is an enlarged fragmentary view in section on line 3—3 of Figs. 1 and 7.

30 Fig. 4 is a perspective view of a liquid tube which constitutes in operation a part of the atomizing tube.

Fig. 5 is a sectional view through one type of receptacle with its closure and illustrating the arrangement of the liquid tube therein.

35 Fig. 6 is a fragmentary side elevation of the pump with the parts that are fixed thereto.

Fig. 7 is an enlarged fragmentary vertical view of the pump.

40 Fig. 8 is a perspective view of another receptacle illustrating the relation of the liquid tube therein, the tube being shown by dotted lines.

Referring to the drawings, 1 represents the 45 barrel or cylinder of an air pump, 2 the piston, 3 the piston rod and 4 the handle thereof.

The cylinder is provided with a head 5 arranged in spaced relation to the front end of the cylinder and having an air discharge opening 6 therein. An annular drip cup wall 7 is secured to the end of the cylinder and coacts with the head in the cylinder wall to provide a drip cup 8.

The atomizing tube 9 is secured to the cylinder head to depend through an opening 10 formed

in the wall of the cylinder and through the cap 11 secured to the underside of the cylinder below the drip cup. This cap is internally threaded to receive the threaded neck 12 of a receptacle 13. The cap is fixedly secured, solder being 60 employed in the embodiment illustrated.

The receptacle is provided with a threaded closure 14, this closure being removed when the receptacle is attached to the pump. The receptacle is provided with a liquid tube 15 which depends therein to a point adjacent the bottom of the receptacle, this liquid tube being adapted to receive the lower end of the atomizing tube when the receptacle is assembled on the pump and constitutes an extension thereof, as clearly 70 shown in Figs. 2 and 3 of the drawings.

The tube 15 is provided with a disk-like head 16 adapted to receive the neck of the receptacle and to receive the cap on the receptacle or the closure 14 as clearly shown in Figs. 2, 3 and 5. 75

Outer and inner gaskets 17 and 18 are preferably arranged between the tube head 16 and the cap 11, the inner gasket 18 being arranged upon and supported by the atomizing tube.

A gasket 19 is preferably provided between 80 the tube head 16 and the end of the neck. Drop openings 20 are formed in the cap which is preferably struck up at 21 to provide a recess 22 for the seam 23 of the pump barrel, see Fig. 3, the openings 20 being formed during this operation. 85 The head 16 is provided with a drip opening 24 so that liquid collected in the drip cup can drain into the receptacle.

In Fig. 1, I illustrate two sizes of receptacles. Fig. 8 illustrates another type of receptacle 25. 90

With this arrangement of parts, the receptacles can be furnished as complete units so that the merchant is not required to stock a complete sprayer for the various sizes of sprays which are in demand, and the customer having acquired the pump portion of the sprayer can secure the spray as desired, and it is not necessary to pour the liquid from the receptacle into which it is secured into the spraying receptacle which is frequently annoying and results in spilling, or the necessity 95 for using a funnel and the cleaning. The pump, when the receptacle is removed, is quite compact and does not have the long projecting atomizing tube as is commonly present.

I have illustrated and described my improvements in an embodiment which I have found very practical. I have not attempted to illustrate or describe certain adaptations and embodiments which I contemplate as it is believed that this disclosure will enable those skilled in the art to em- 105 110

body or adapt my improvements as may be desired.

Having thus described my invention, what I claim as new and desire to secure by Letters Patent, is:

1. In a sprayer, the combination of an air pump comprising a cylinder provided with a head spaced from its end and having a discharge opening therein, an outer wall member secured to said cylinder and coacting with said head to provide a drip cup, a threaded cap secured to said cylinder below said drip cup, an atomizing tube disposed through said cap and cylinder and fixedly secured with its outer end in operative relation to said pump discharge orifice, a receptacle having a threaded neck adapted to receive a threaded closure and detachably engaging said cap on said pump, a liquid tube depending within said receptacle and provided with a disk-like head resting on the neck thereof, said liquid tube receiving said atomizing tube and constituting an extension for said atomizing tube, and outer and inner gaskets interposed between said cap and liquid tube head and a gasket interposed between said liquid tube head and receptacle neck, there being drain openings in said drip cup, cap, and liquid tube head.

2. In a sprayer, the combination of an air pump comprising a cylinder provided with a head spaced from its end and having a discharge opening therein, an outer wall member secured to said cylinder and coacting with said head to provide a drip cup, a threaded cap secured to said cylinder below said drip cup, an atomizing tube disposed through said cap and cylinder and fixedly secured with its outer end in operative relation to said pump discharge orifice, a receptacle having a threaded neck adapted to receive a threaded closure and detachably engaging said cap on said pump, and a liquid tube depending within said receptacle and provided with a disk-like head resting on the neck thereof, said liquid tube receiving said atomizing tube and constituting an extension for said atomizing tube, there being drain openings in said drip cup, cap and liquid tube head.

3. In a sprayer, the combination of an air pump comprising a cylinder provided with an air discharge opening, a threaded cap secured to said cylinder, an atomizing tube disposed through said cap in operative relation to said discharge opening, a drip cup above said cap, a receptacle having a threaded neck adapted to receive a threaded closure and detachably engaging said cap, a liquid tube depending within said receptacle and provided with a disk-like head resting on the neck, said liquid tube receiving said atomizing tube and constituting an extension for said atomizing tube, and outer and inner gaskets interposed between said cap and liquid tube head and a gasket interposed between said liquid tube head and receptacle neck, there being drain openings in said drip cup, cap and liquid tube head.

4. In a sprayer, the combination of an air pump comprising a cylinder provided with an air discharge opening, a threaded cap secured to said cylinder, an atomizing tube disposed through said cap in operative relation to said discharge opening, a drip cup above said cap, a receptacle having a threaded neck adapted to receive a threaded closure and detachably engaging said cap, and a liquid tube depending within said receptacle and provided with a disk-like head resting on the neck, said liquid tube receiving said atomizing tube and constituting

an extension for said atomizing tube, there being drain openings in said drip cup, cap and liquid tube head.

5. In a sprayer, the combination of an air pump comprising a cylinder provided with an air discharge opening, a threaded cap secured to said cylinder and having an air and drip opening, an atomizing tube disposed through said cap in operative relation to said discharge opening, a receptacle having a threaded neck adapted to receive a threaded closure and detachably engaging said cap, a liquid tube depending within said receptacle and provided with a disk-like head resting on the neck and having an air and drip opening, said liquid tube receiving said atomizing tube and constituting an extension for said atomizing tube, and outer and inner gaskets interposed between said cap and liquid tube head and spaced to provide an air and drip passageway between said openings and a gasket interposed between said liquid tube head and receptacle neck.

6. In a sprayer, the combination with an air pump provided with an air discharge way, of an atomizing tube operatively associated with said air discharge way, a cap secured to said pump with said atomizing tube disposed centrally of said cap, a drip cup operatively associated with said atomizing tube, a receptacle detachably engaging said cap, a liquid tube depending within said receptacle and provided with a head resting on the top of said receptacle, said liquid tube receiving said atomizing tube and constituting an extension for said atomizing tube, there being drain openings in said drip cup, cap and liquid tube head.

7. In a sprayer, the combination with an air pump provided with an air discharge way, of an atomizing tube operatively associated with said air discharge way, a cap secured to said pump with said atomizing tube disposed centrally of said cap, a receptacle having a neck adapted to receive a closure and detachably receiving said cap, a liquid tube depending within said receptacle and provided with a head resting on the neck, said liquid tube receiving said atomizing tube and constituting an extension for said atomizing tube, and inner and outer gaskets interposed between said cap and liquid tube head, there being drain and air openings in said cap and head, and said gaskets being spaced to provide a connecting passageway between said openings.

8. In a sprayer the combination of an air pump comprising a cylinder provided with an air discharge opening, a cap secured to the under side of said cylinder, an atomizing tube operatively associated with said air discharge opening and depending through said cap with its lower end terminating adjacent the plane of the lower edge of the cap, a receptacle having a neck adapted to receive a closure and detachably engaging said cap on said pump, and a liquid tube depending within said receptacle and provided with a disk-like head at its upper end resting on the neck thereof, said liquid tube and atomizing tube having a telescoping slip connection when the receptacle is in engagement with said cap, said head being clamped between the neck and the cap when the receptacle is engaged with the cap and being freely removable from the receptacle when the receptacle is removed from the cap.

9. In a sprayer the combination of an air pump comprising a cylinder provided with an

air discharge opening, a cap secured to the under side of said cylinder, an atomizing tube operatively associated with said air discharge opening and depending through said cap with its lower end terminating adjacent the plane of the lower edge of the cap, a receptacle having a neck adapted to receive a closure and detachably engaging said cap on said pump, and a liquid tube depending within said receptacle and provided 5 with a head at its upper end resting on the neck thereof, and clamped between the neck and the cap when the receptacle is in engagement with the cap, said liquid tube and atomizing tube having a slip connection when the receptacle is in engagement with said cap.

10 in engagement with said cap.

15 10. In a sprayer the combination of an air

pump comprising a cylinder provided with an air discharge opening, a cap secured to the under side of said cylinder, an atomizing tube operatively associated with said air discharge opening and depending through said cap with its lower end terminating adjacent the plane of the lower edge of the cap, a receptacle having a neck adapted to receive a closure and detachably engaging said cap on said pump, and a liquid tube depending within said receptacle and provided 80 with a head at its upper end resting on the neck thereof, and clamped between the neck and the cap when the receptacle is in engagement with the cap, said liquid tube and atomizing tube having a slip connection when the receptacle is in engagement with said cap.
